KEY MECHANISM

Gustave A. Ungar, Pelham Manor, N. Y., assignor
to S. & S. Corrugated Paper Machinery Co.,
Inc., Brooklyn, N. Y., a corporation of New York

Application March 4, 1938, Serial No. 193,837

7 Claims. (Cl. 287—52.05)

My present invention relates to novel key constructions, and it is particularly directed to improvements in keys for securing rotary slotter knives to a shaft.

5 In one device to which this invention may be applied, slotting knives in the form of ring-disks are placed upon heads or carriers located on a rotatable shaft at specified distances apart. The position of the slotters are secured by set or lock 10 screws passing through a key to the shaft. The set screws are reached by a suitable wrench passed between two of the slotting knives forming the female side of the knife. Such an arrangement has been found necessary in order to 15 permit placing the slotter knives in closely spaced relation.

In the preferred illustration, the slotter knives are used for slotting corrugated paper boards or 20 partitions for paper boxes. In the course of manipulation of a large number of such boards, the slot or hollow hexagon hole used for inserting a turning instrument or wrench for the set screw wears cut or becomes filled with accumulated 25 glue and paper, making it necessary to dismantle the knives from the heads when it is desired to insert new lock screws. This is ordinarily a slow and tedious operation owing to the multiplicity of parts involved.

30 My present invention is directed to a key construction whereby it is possible to bodily remove the lock screws when it is necessary to clean them for resetting or to replace the lock-screw when worn, simplifying a heretofore slow and expensive operation.

35 It is accordingly an object of my present invention to provide a novel key construction.

Another object of my present invention is to provide a novel means for removing the key and the set-screw from locked position on a shaft.

40 Still another object of my invention is to provide means for rapid removal and replacement of worn or broken set-screws from locked position on a shaft.

45 Other objects of my invention will become apparent in the following detailed description taken in connection with the drawing, in which:

Figure 1 is an end sectional view of a shaft with a disk in place, showing the relationship of 50 the disks with the material to be cut or formed, and the novel key unit.

Figure 2 is a cross-sectional view through the key unit taken along 2—2 of Figure 1, with the key in locked position.

55 Figure 3 is a partial view corresponding to

Figure 2, showing the key and set-screw out of locked position.

Figure 4 is a perspective view of the novel key and set-screw unit.

Referring now to Figure 1, a first knife unit, 5 consisting of the semi-circular segments 10 and 11, is mounted on rotatable shaft 12, by means of clamping head 13 and screws 20. The blades 10 and 11 are fitted against an annular projection 13a of clamping head 13. A slot 15 cut into shaft 12, and one at 15' cut into clamping head 13, form a keyway, which as is well known, when fitted with a suitable key, prevents the turning of the knife unit 10—11 with respect to the shaft 10 15 12.

A second knife unit 10'—11' is attached to head 13 by the screws 20 to cooperate with knife 10—11. These parallel knife groups form a female cutting edge for knife segment 16, attached to head 17 with clamping screws 17' as 20 shown in Figure 1. This arrangement is for cutting slots into the material 18 fed therebetween.

A third pair of blades 10'' and 11'' is also attached to head 13 by the screws 20. Knives 10'' and 11'' are spaced from knives 10—11' by spacing ring 26; the thickness of ring 26 is less than that of the flange projection 13a of head 13. When it is desired to cut slots narrower than 25 13a, it is only necessary to replace male segment 16 in head 17 with a knife segment of approximately the same thickness as ring 26 and arrange the thinner blade segment to cooperate with blades 10' and 11' and 10'' and 11''. It is 30 accordingly possible to readily change to either 35 of the two standard slot sizes.

In accordance with my invention, a simple 40 means is provided for simultaneously removing the set-screw and key together, without dismantling or otherwise disturbing the setting and alignment of the various cutting disks. The principle of my invention will be better understood from an examination of the perspective view thereof, Figure 4. The key 19 is shown provided with a spring clip 21. Key 19 is chamfered at 45 31 to allow for the depression of spring 21 in a manner to be described. A block 23 is fitted over the head of the lock-screw 22. Block 23 is provided with a hole 32 for permitting the insertion 50 of a suitable screw-turning tool to the head of screw 22.

Block 23 fits into a recess 23' in blade 10 and a recess 23'' in blade 10'. Block 23 presses against blades 10 and 11' and provides a firm abutment 55 for set screw 22 in clamping key 10 against shaft

12. A portion 27 is cut away on the head 13 above the key-way 15' therein to permit insertion of the projection portion screw 22 from the right end. The length of the slot 27 fixes the position 5 of the key 19 in the knives, and proper snapping of the spring clip 21 into position against the shoulder of the clamping head 13 as shown in Figure 2. The spring 21 normally locks the key 19 from transverse displacement.
- 10 When the key is in position as shown in Figure 2, one end of block 23 abuts spacer ring 26. When the lock screw 22 is turned in such a direction that it moves upwards, block 23 and the key 19 are forced to be seated tightly in the keyway 15. Block 23 acts as a protection to the head 10 of the screw 22 to prevent unequal torsional forces or excessive wear on the top surface of screw 22.

As long as the hollow hexagonal wrench hole 20 30 in the head of set-screw 22 remains unclogged, the screw 22 may be loosened in the ordinary manner.

Should the wrench hole 30 become clogged or worn, spring 21 is depressed and the key 19 25 driven out of the keyway, and the lock screw can be quickly replaced.

Having described a preferred modification and application for my invention, I am aware that modifications may be made therein which fall 30 within the broader spirit and scope thereof, and furthermore that its application is not limited to slotter-heads, but is generally applicable where keyway constructions are used; I therefore do not intend to be limited except as set forth in 35 the following claims.

I claim:

1. A shaft and a member secured thereto; a key mechanism for securing said member on said shaft to prevent rotation of said member with 40 respect to said shaft comprising a key; keyways in said member and said shaft comprising opposed slots registerable with each other; said key being insertable in said keyways; spring means associated with said key for holding said key in 45 position against transverse displacement; and means for securing said key in position including a screw device cooperative with said key.

2. A shaft and a member secured thereto; a key mechanism for securing said member on said 50 shaft to prevent rotation of said member with respect to said shaft comprising a key; keyways in said member and said shaft comprising opposed slots registerable with each other; said key being insertable in said keyways; spring 55 means associated with said key for holding said key in position against transverse displacement; and means for securing said key in position including a screw device cooperative with said key and a block arranged to coact with the head of 60 said screw device.

3. A key mechanism comprising a key; means associated with said key for holding said key in position against transverse displacement; and means for locking said key in position including 65 a lock-screw threaded in said key, and a block arranged to coact with the head of said lock-screw having an opening above a gripping recess in said lock-screw.

4. A key mechanism for securing a member to a shaft comprising a key adapted to fit into opposed slots in said shaft and member; means associated with said key for holding said key in position against transverse displacement on said 5 shaft; and means for locking said key in position between said shaft and member including a lock-screw device cooperative with said key, and a block arranged to coact with the head of said lock-screw device, said block being positionable 10 in a groove in said member whereby said lock-screw device exerts pressure between said key and said block when properly rotated to lock said key in position.

5. A key mechanism for securing a member to 15 a shaft comprising a key adapted to fit into opposed slots in said shaft and member, having a depressed region therein; spring means associated with said key opposite the depressed region being adapted to grip said member for holding 20 said key in position against transverse displacement on said shaft; and means for holding said key in position between said shaft and member including a lock-screw threaded in said key and a block arranged to coact with the head of said 25 lock-screw.

6. A key mechanism for securing a member to a shaft comprising a key adapted to fit into opposed slots in said shaft and member, having a depressed region therein; spring means associated with said key opposite the depressed region 30 being adapted to grip said member for holding said key in position against transverse displacement on said shaft whereby the gripping action of said spring means may be released by depressing the spring means towards the chamfered region; and means for holding said key in position between said shaft and member including a lock-screw threaded in said key and a block arranged to coact with the head of said lock-screw, 40 said block being positionable in a groove in said member whereby said lock-screw exerts pressure between said key and said block when properly rotated to lock said key in position.

7. A key mechanism for securing a member 45 to a shaft comprising a key adapted to fit into opposed slots in said shaft and member, the upper surface of said key being chamfered across one corner thereof; a plate for holding said key in position against transverse displacement 50 on said shaft, said plate having a transversely projecting edge adapted to grip said member, said projecting edge being positioned opposite the chamfered corner whereby the gripping action of said plate may be released by depressing the 55 projecting edge towards the chamfered region; and means for securing said key in position between said shaft and member including a screw device cooperative with said key, and a block arranged to coact with the head of said screw device 60 having an opening above a gripping recess in said screw device, said block being positionable in a groove in said member whereby said screw device exerts pressure between said key and said block when properly rotated to lock said key in position. 65
